DESIGN FOR A PERFUME TESTING STRIP HOLDER

Albert G. Nickstadt, New York, N. Y., and Alfred
H. Moeller, Pompton Lakes, N. J.

Application January 26, 1946, Serial No. 126,018

Term of patent 7 years

(Cl. D80—9)

To all whom it may concern:

Be it known that we, Albert G. Nickstadt and Alfred H. Moeller, citizens of the United States, and residents respectively of the Borough of Manhattan, in the city, county, and State of New York; and of Pompton Lakes, in the county of Passaic and State of New Jersey, have invented a new, original, and ornamental Design for a Perfume Testing Strip Holder, of which the following is a specification, reference being had to the accompanying drawing forming a part thereof.

Fig. 1 is a plan view of a perfume testing strip holder, embodying our new design;

Fig. 2 is a front elevation of the holder;
Fig. 3 is an end elevation of the holder, viewed from the right of Fig. 2;

Fig. 4 is a back elevation of the holder; and
Fig. 5 is a vertical section, taken on the line V—V of Fig. 4, looking in the direction of the arrows.

What we claim is:

The ornamental design for a perfume testing strip holder, substantially as shown.

ALBERT G. NICKSTADT.
ALFRED H. MOELLER.
